Samuel W. Gibbs of Albany, N.Y. Ass't to
Jagger, Treadwell & Perry.

Setters Patent No. 357 - Dated Mar. 4, 1851.

The Schedule referred to in these Letters Patent and making part of the same.

To whom it may concern:

Be it known, that I,

Samuel W. Gibbs of the City of Albany and State of New York, have produced a new ornamental design for a Cooking Stove, the Stove, so ornamental, being known as the Forest Queen Stove, and I hereby declare that the annexed and accompanying drawings, are full and accurate delineations of the ornamental parts with their several ornaments - the side plate, not shown, being similar to that shown, and where portions of parts, or plates, are shown, the parts not shown, being symmetrical with them, and similarly ornamented.

What I claim as my production & desire to secure by Letters Patent, is the combination and arrangement of ornamental figures and forms represented in the accompanying drawings, forming together an ornamental design for the side of a Cooking Stove, and the back & front plates of the elevated oven.
